US0D1029748S

(12) **United States Design Patent** (10) **Patent No.:** **US D1,029,748 S**
(45) **Date of Patent:** **** Jun. 4, 2024**

(54) **BATTERY MODULE**

(71) Applicant: **Samsung SDI Co., Ltd.**, Yongin-si (KR)

(72) Inventors: **Kwangsoo Bae**, Yongin-si (KR); **Deayon Moon**, Yongin-si (KR); **Seokbin Yoon**, Yongin-si (KR)

(73) Assignee: **Samsung SDI Co., Ltd.**, Yongin-si (KR)

(**) Term: **15 Years**

(21) Appl. No.: **29/790,780**

(22) Filed: **Dec. 14, 2021**

(30) **Foreign Application Priority Data**

Jun. 17, 2021 (KR) 30-2021-0028826

(57) **CLAIM**

The ornamental design for a battery module, as shown and described.

DESCRIPTION

FIG. 1 is a front perspective view of the battery module;

FIG. 2 is a front view thereof;

FIG. 3 is a rear view thereof;

FIG. 4 is a left side view thereof;

FIG. 5 is a right side view thereof;

FIG. 6 is a top view thereof; and

FIG. 7 is a bottom view thereof; and,

FIG. 8 is a front perspective view of a plurality of the battery modules coupled to each other.

The broken lines in the drawings depict portions of the battery module that form no part of the claimed design.

1 Claim, 8 Drawing Sheets
